UNITED STATES PATENT OFFICE.

LUMAN H. LEWIS, OF SAN JOSÉ, CALIFORNIA.

MITER-BEVEL.

SPECIFICATION forming part of Letters Patent No. 361,532, dated April 19, 1887.

Application filed November 27, 1886. Serial No. 220,034. (No model.)

To all whom it may concern:

Be it known that I, LUMAN H. LEWIS, of San José, in the county of Santa Clara and State of California, have invented certain new and useful Improvements in Miter-Bevels; and I do hereby declare that the following is a full, clear, and exact description thereof, reference being had to the accompanying drawings, and to the letters of reference marked 10 thereon, which form part of this specification, in which—

Figure 1 is a top view showing my improved miter-bevel applied in one position for marking a piece of timber. Fig. 2 is a similar view, showing the bevel in a different relation to the piece of lumber. Fig. 3 shows the bevel used as a right angle. Fig. 4 is a side view, partly broken, of the bevel. Fig. 5 is a detail of the gage-plate.

20 This invention relates to improvements in what are called in carpentry "miter-gages," such as are used to quickly and readily score or mark timber at any desired angle to be cut thereon and in the making of polygonal frames.

One of the main features of the invention is the extension of the edge or blade, by means of which the marking is done on both sides of the bar or leg to which said edge or blade is 30 pivoted, so that the marking can be done from either arm of said blade or on each side of its pivotal point.

This invention further consists in certain details of construction and arrangement hereinafter described, and pointed out in the appended claims.

Referring to the accompanying drawings, A designates the stock of the device, rectangular in cross-section, and split or bifurcated, as at 40 a^2 , for nearly its entire length, the said bifurcation being horizontal. The sides of the stock A are straight and parallel to each other, and its end a' , from which the bifurcation runs, is rounded and has the blade B pivoted to it, 45 the said blade entering the bifurcation and the pivot-screw b being at about its center.

b' is a thumb-nut on the extended end of said screw, to retain the parts of the device together at any desired angle.

50 C is a segmental plate formed on the inner edge of the blade B, and entering the bifurcation of the bar A. The said segmental plate

has a straight edge, c, inclined at an angle of forty-five degrees to the marking-edge of the blade, and the inner edge of the blade is 55 notched or cut away at c' , the point of junction of the edge c and the inner edge of the blade, so that the edges c will be extended to the side of the stock A, and can be set at varying angles thereto, as shown. The segmental 60 plate is scored on one side with lines marked 3, 4, 5, 6, 7, 8, &c., any of which can be brought into exact alignment with the adjacent sides of the bar A, which sides have metallic plates secured to them, so as to afford a 65 more perfect and straighter edge to bring the lines to than wood would give. The lines, as marked, give the various angles of polygons having a corresponding number of sides, and by setting the blade B with one of its scores 70 or lines coincident with the metallic plates of the stock, its outer continuous edge will give the proper angle for cutting the adjoining ends of blocks to form such polygons. The segmental plate is also scored with a line, D, which stands 75 at an angle of forty-five degrees to the edge c, and when said line is brought to correspond with the side of the bar, as described, the blade will be at right angles to said bar, and the workman can score at right angles across 80 a piece of timber on either side, the notch c' permitting him to score one edge, c, from the stock to the outer end of said edge, and he can also score at an angle of forty-five degrees on one side by means of the edge c, as shown 85 in Fig. 3.

In Fig. 1 the device is shown in position to score a piece of timber where the angles are to diverge outward from the straight to the irregular side. In this case the scoring is done 90 on the arm E of the blade. In Fig. 2, where the device is in position to score angles that converge inward from the straight to the irregular side, the scoring is done on the arm E'.

I am aware that the scored segmental plate 95 has been used in miter-gages—such, for instance, as is shown in patent of Thompson, granted October 12, 1858, and numbered 21,784—and such I do not claim, broadly; but

What I do claim is—

1. The combination, in a miter-gage, of the stock A, the scoring-blade B, pivoted near its center to said bar, as described, and the scored segmental plate C, provided with the edge c at

an angle of forty-five degrees, with the scoring-edges of blade B and the mark or line D, at right angles to said edges, and the notch c' at the junction of edge c and blade B, substantially as specified.

2. In a miter-gage, the combination, with the stock A, of a scored segmental plate, C, formed with an extension-blade on both sides thereof and having the notch c' , all as and for to the purpose set forth.

3. In a miter-gage, the combination, with the stock A, constructed as described, of a plate,

B, having a scored segmental plate, C, provided with a straight marking-edge, the notch c' , to form a continuation of said edge, and the 15 blades E E', all constructed and arranged substantially as and for the purpose described.

In testimony that I claim the foregoing as my own I affix my signature in presence of two witnesses.

LUMAN H. LEWIS.
